UNITED STATES PATENT OFFICE.

GEORGE HARDING, OF SPOKANE, WASHINGTON.

APPARATUS FOR REINFORCING POLES.

1,243,933.

Specification of Letters Patent. Patented Oct. 23, 1917.

Application filed April 14, 1916. Serial No. 91,159.

To all whom it may concern:

Be it known that I, GEORGE HARDING, a citizen of the United States, residing at Spokane, in the county of Spokane and State of Washington, have invented a new and useful Apparatus for Reinforcing Poles, of which the following is a specification.

The present invention appertains to means for reinforcing poles that have been weakened through decay, and it is the object of the invention to provide novel and improved means for the reinforcement of telephone, telegraph, and other poles.

The present invention has for its object, the provision of an apparatus for providing a reinforced concrete jacket embracing the pole within the ground and projecting out of the ground, whereby the pole is able to withstand the strains to which it is subjected, even though the pole was previously rotted or decayed.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a vertical section of the apparatus as applied to a pole ready to receive the concrete, portions being shown in elevation.

Fig. 2 is a horizontal section taken on the line 2—2 of Fig. 1.

Fig. 3 is an elevation of the concrete forms, a portion of the lower one being broken away.

Fig. 4 is a detail view of one of the spikes and its clip.

Fig. 5 is a reduced detail view illustrating the concrete jacket upon the pole to reinforce it.

The pole is designated at 1, which may be taken to represent any wooden or equivalent pole or post, planted in the ground for supporting wires or other overhead structure. The first step in reinforcing the

pole consists in digging a hole in the ground around the pole, to expose the rotted or decayed portion thereof, which is removed by a chisel or other implement, as at 3, to expose the unrotted wood, which is painted by a preservative or water proof compound to a suitable point above the surface of the ground to which the concrete jacket is to extend.

Following the foregoing preliminary steps, a metallic reinforcing structure for the concrete is built up around the post. This structure embodies a pair of upper rings 4 surrounding the post, and a pair of lower rings 5 also surrounding the post adjacent the surface of the soil. The upper rings 4 are of smaller diameter than the lower rings 5, and when necessary additional rings can be used to provide added strength. The rings 4 are all split, and have overlapped ends, which are at different points about the pole to avoid the possibility of the ends of the rings being in a vertical line, which would be objectionable. These rings 4 and 5, which are bent from rods, bars, or other suitable stock, are supported by spikes 6 driven into the post 1 immediately above the rings. Clips 7 engage the shanks of the spikes adjacent the heads thereof, for supporting the rings. The clips 7 are preferably formed from sheet metal having the slits 8 through which the spikes 6 extend, and said clips 7 have the lower hooks 9 engaging under the rings to support them. Any number of spikes may be used for supporting the rings, as is found most advantageous, and said spikes serve to rigidly connect the rings with the post. Vertical bars or rods 10 are then inserted within the rings 4—5, and also shorter rods or bars 11, which bars are suitably spaced apart, as seen in Fig. 2, they preferably being in alternate arrangement. The bars 11 terminate a short distance below the surface of the ground, while the bars 10 are sufficiently long to be driven into the ground at the bottom of the hole 2. The bars 10—11 bear against the rings from the inside, and said bars and rings are secured together by tie wires 12 or the like, whereby to provide a rigid reinforcing frame surrounding the post adjacent and above the

cut away portion 3. The upper ends of the bars 10-11 are provided with outturned hooks 13 engaging over the uppermost ring 4, to limit the downward movement of the bars, and to connect the upper ends of the bars and the uppermost ring. The amount of stock used in this reinforcing structure or frame depends upon the circumstances, and may be varied.

10 The next step consists in disposed superposed concrete forms 14 and 15 around the reinforcing structure, the lower form 14 being cylindrical, while the upper one 15 which is seated thereon is frusto-conical.

15 Each form is formed from a blank of sheet metal which is rolled into circular form, with the edge portions overlapping or meeting. The form 14 extends to a point near the rings 5, while the form 15 extends from

20 the upper end of the form 14 to a point slightly above the uppermost ring 4. The form 15 is adapted to seat against the heads of the spikes, to be supported thereby, in addition to possibly resting upon the upper 25 end of the form 14.

Each of the forms 14-15 is held contracted at the proper diameter, by means of a chain 16 or other flexible element embracing it, and held in place by straps 17 attached to the form, the ends of the chain being connected by a suitable coupling 18.

When the apparatus is thus put in place, concrete of suitable nature is poured into the forms 14-15, and is tamped therein.

35 The concrete will surround the rings 4-5 and bars 10-11, as well as the spikes 6, and the concrete is sloped off at the upper end of the form 15 by means of a trowel or other suitable implement, but before the forms 40 are completely filled with concrete, an annular rubber form 19 is placed upon the post 1, at the upper end of the form 15 and is tacked or nailed thereto. The concrete is sloped from the upper edge of the form 19.

45 The apparatus is then preferably covered with sacks, or the like, which are kept in a moistened condition for a sufficient period of time, until the concrete has set. The forms are then removed, and the hole 2 is

50 filled up; so as to pack the ground around the concrete jacket 20 which now embraces the pole. Said jacket will be embedded in the ground and will project out of the ground, the projecting portion of the jacket 55 being of tapered form, while the basal portion thereof is of cylindrical form. The upper end of the jacket 20 is provided with a recess 21 formed by the form 19, in which an elastic water proof compound 22 is placed, to prevent water entering the jacket and rotting the pole. The pole when thus reinforced will be of substantial construction, to renew the life thereof.

Due to the fact that the pole is painted 65 with a waterproof compound, this prevents

the pole from becoming wet by the water used in the concrete, or prevents the wood from absorbing the moisture from the concrete, thereby avoiding the expansion of the pole and the breaking of the concrete before it has had time in which to set. If the concrete should be cracked or ruptured before it is set, this would naturally spoil the concrete jacket. Poles which are completely rotted off can be reinforced just as readily as those that are only partially rotted off. The concrete used consists of cement, clean sharp sand and crushed rock slag or gravel not larger than 2" mesh and not smaller than $\frac{1}{2}$ " mesh. The waterproof compound should be elastic in order to expand and contract with the pole, and to form a perfect closure.

The spikes or nails 6 can be disposed either above or below the rings, and when driven into place spring the rings to the desired diameter, and also serve to center the concrete forms about the reinforcing structure, as well as to partly support the upper form. The rings are adjustable to the size of the pole since the rings are split. The concrete forms can be used on all poles of ordinary sizes, and the chains serve to adjust the forms to the particular pole. The lower form can have clips or other means for facilitating the removal thereof from the hole.

Having thus described the invention, what is claimed as new is:

1. The combination with a pole, of an annular reinforcing structure surrounding it, and members entering the pole and supported thereby; said members extending across portions of said structure and having their outer ends projecting outwardly from said structure for spacing a form therefrom, said members being provided with portions between their ends projecting at an angle therefrom and moved inwardly into engagement with said portions of said structure for supporting said structure from said members and holding the structure in position about the pole.

2. The combination with a pole, of rings surrounding the pole; vertical bars assembled with the rings, spikes driven into the pole and extending across portions of said rings, and hooks carried by the spikes and moved inwardly into engagement with the rings for supporting them from the spikes, and the outer ends of the spikes projecting outwardly from the rings to space a form therefrom.

3. An apparatus for reinforcing poles comprising split rings to surround a pole, spikes adapted to be driven into the pole, clips carried by said spikes and engageable with said rings to support them, and vertical bars within and attached to said rings.

4. An apparatus for reinforcing poles comprising split rings to surround a pole,

spikes adapted to be driven into the pole across said rings and having heads at their outer ends, clips engaging the shanks of the spikes adjacent the heads thereof and upon the outer sides of said rings, said clips having hooks engaging the rings to support them, and vertical bars assembled with said rings.

In testimony that I claim the foregoing as my own, I have hereto affixed my signature in the presence of two witnesses.

GEORGE HARDING.
